UNITED STATES PATENT OFFICE.

JOHN C. KRIEG AND FRANK FISHBAUGH, OF NEWARK, OHIO.

DESIGN FOR A RUBBER HEEL.

Application filed May 16, 1922. Serial No. 2,272. Term of patent 14 years.

To all whom it may concern:

Be it known that we, JOHN C. KRIEG and FRANK FISHBAUGH, citizens of the United States, residing at Newark, in the county of Licking and State of Ohio, have invented a new, original, and ornamental Design for a Rubber Heel, of which the following is a specification, reference being had to the accompanying drawing, forming part thereof.

Figure 1 is a face view of a rubber heel, showing our new design.

Figure 2 is a front elevation thereof.

We claim:

The ornamental design for a rubber heel, as shown.

JOHN C. KRIEG.
FRANK FISHBAUGH.
